WALTER ALDERDICE, OF BROOKLYN, NEW YORK, ASSIGNEE TO ALFRED W. CHANNING, INC., OF NEW YORK, N. Y., A CORPORATION OF NEW YORK.

METAL FURNACE.

Application filed September 17, 1926. Serial No. 136,096.

My invention relates to furnaces for melting down metal and while not limited to a specific use, it is especially adapted for furnaces for melting down type metal in printing establishments. My invention is related more particularly to the device for pouring the molten metal from the metal pot into the moulds in which pigs are cast. It is desirable to have a movable spout in furnaces 10 of this type in order that it may be swung in a wide arc across the mould to pour the metal into as many cavities as possible in the mould. Heretofore, it has been proposed to attach a spout pivotally to the lower end of the metal pot within the furnace; and to extend this spout through an opening in the side of the shell of the furnace to conduct the metal into the mould. One disadvantage of this construction is that it is 20 difficult to make a durable and reliable pivotal joint between the spout and the metal pot. Furthermore, when the metal has been allowed to cool or chill, the joint between the spout and metal pot becomes rigid and 25 cannot be moved until the metal in the pot and in the spout have been melted. Other devices have been proposed which it is not necessary to describe in detail, but each of the former devices is open to one or more 30 similar objections. The object of my present invention is to provide a spout which may be permanently or immovably attached to the metal pot and which is led through an opening in the shell of the furnace where it 35 conducts the molten metal into a trough-like member which is adapted to be moved in the arc of a circle, and this trough-like member is itself provided with a movable spout which moves therewith and which 40 finally conducts the molten metal into the mould. I am enabled to obtain a wide swing with this movable spout and at the same time employ the stationary spout directly connected with the metal pot. In 45 order to maintain the trough-like member sufficiently heated to prevent the metal from chilling within it and the movable spout, I provide suitable heating means for heating one or both ends of the trough-like member, and the heating means is disposed within the casing or shell of the furnace in order that the fumes from the burner will 50 pass out with the fumes of the burner which heats the metal pot. Furthermore, by ar-

ranging this heating means within the shell 55 of the casing, all danger of fire is eliminated and the device will meet the requirements of the fire underwriters. Other objects and advantages of the invention will be set forth in the detailed description of my invention 60 hereinafter.

In the drawings forming part of this application,

Figure 1 is a front elevation of a portion of a furnace to which my invention has been 65 applied,

Figure 2 is a side elevation thereof,

Figure 3 is a sectional view taken on the line 3—3 of Figure 2,

Figure 4 is a plan view on a larger scale, 70 of the trough member, removed from the furnace,

Figure 5 is an inverted view of a portion thereof,

Figure 6 is a sectional view taken on the 75 line 6—6 of Figure 4, and

Figure 7 is a sectional view taken on the line 7—7 of Figure 4.

I have illustrated my invention applied to a metal furnace such as may be used for 80 melting down type metal for casting into pigs. As shown in the drawing, this furnace comprises a casing or shell 1 which encloses the metal pot 2 shown in dotted lines in Figure 2; and it will be understood 85 that some form of heater is provided below the metal pot and in practice it is common to employ gas burners for this purpose. The metal flows from the metal pot through the central connection 3 and it must be conducted beyond the shell into position to be 90 poured into suitable moulds. I have provided a stationary pipe or spout 4 which is fixed to the outlet connection 3 of the metal pot in any suitable manner, and as this 95 spout remains stationary the connection may be such as will not leak when the molten metal passes through it. This spout extends forwardly from the bottom of the metal pot and preferably slightly downwardly to cause the metal to flow freely through it; and the outer end 5 of this spout is shown turned downwardly to discharge 100 the molten metal into the swinging trough.

The trough 6 is preferably made of cast 105 metal although other materials may be used; and it consists of a body 7 curved horizontally. While the curvature of this trough is

not limited to a specific form, I prefer to make it curved on the arc of a circle, the center of which is as near the center line of the metal pot as is consistent with the other proportions of the furnace and pouring device. The upper side of the trough is provided with inner and outer, preferably concentric, walls 8, 9 and at each end of the trough there is an end wall 10 connected between the front and rear walls, these several walls forming a trough-like compartment 11, adapted to receive and temporarily hold the molten metal. I have shown this compartment as tapered, as shown in Figure 6, so that it is wider at the top and decreases in width towards the bottom. The inner and outer walls 8, 9 in the preferred construction, are formed on the arcs of concentric circles and are preferably less than a semi-circle in extent. Beyond the ends of the compartment 11 the trough member is provided with extensions 12 which serve the purpose to be hereinafter described; and these extensions are preferably curved on arcs of smaller radii than the arc of curvature of the remainder of the trough member, and are so positioned, as shown in Figure 4, that when the trough member is rotated in the opening of the casing, these extensions 12 will move in and out of the slot 13 in the shell, which slot is substantially no larger than if the slot were made merely to accommodate the portion of the trough containing the metal compartment.

The trough member is supported in a horizontal position by means of brackets 14 which are bolted or otherwise secured against the wall of the casing 1 of the furnace. The brackets have secured to them a horizontal, arcuate plate 15 on which the trough member directly rests. There are brackets 16 bolted to the inner and outer faces of the trough member by means of bolts 17 and these extend downwardly to straddle the arcuate plate 15 and are turned horizontally at their lower ends 18 toward each other, to engage under the plate 15. These latter brackets hold the trough member in position upon the supporting plate 15 and also permit the trough member to be rotated thereon. The rotation of the trough member is limited by means of a stop member 19 which is secured to the under side of the trough member and which is adapted to contact with one of the brackets 16 in the extreme position of the trough member upon the supporting plate 15. A similar stop member may be provided adjacent the opposite end of the trough for engaging another of the brackets 16 to limit the swing of the trough member in the opposite direction.

The trough chamber 6 is preferably inclined from the ends of the trough toward the center; and in Figure 1 I have shown

by the dotted line 20 how the bottom wall of the trough thus inclines downwardly toward the center. At the center of the trough member there is an outlet opening 21 in line with a spout connection 22 which latter may be cast integrally with the trough member, as shown at Figure 7. This connection member has attached to it a pouring spout 23 the bore of which is in communication with the bore of the connecting member 22; and the free end of this pouring spout is preferably turned downwardly as shown at 24 to deliver the molten metal in the top of the mould (not shown) which may be placed under the spout. I have shown a handle 25 attached by a set screw 26 to the connection member 22 which handle is adapted to be used for swinging the trough member around upon its supporting plate 15; and this motion carries the movable spout 23 with the trough member.

There will be a tendency for the metal to chill slightly in the trough member on account of its exposure to the air, and this is overcome by heating the trough member to prevent the metal from chilling. The trough member, as above described, is provided with extensions 12 which project inside the wall of the furnace. When the trough member is turned upon its support some part of it will always be projected within the furnace wall, even though one end withdraws to the outside of the furnace wall. I have arranged within the furnace wall a pipe 27 which is adapted to be connected with any source of fuel supply such as a gas feed pipe; and this pipe is connected with a branch pipe 28 extending horizontally near the front of the furnace wall 1. This cross pipe is provided at opposite ends with upturned sections the upper ends of which form gas burners 29 which are disposed inside of the furnace wall, and adjacent the slot 13 in which the trough member moves. The burners are so placed that the flame from each will be projected against the under side of both of the extension members 12 when the trough member is in its intermediate position. When the trough member is swung to the right or left one or the other of the extension members 12 will be temporarily removed from its particular burner, but the opposite burner will continue to heat either the opposite projecting member 12 or the under part of the trough. It will be apparent from the above that at all times the trough member as a whole is heated by either both burners 29 when the trough is in the central position, or by one of the burners when the trough member is swung to the right or left. By placing these burners within the furnace wall the products of combustion from them will be conducted away the same as the waste products are conducted from the burners which heat the

metal pot. Furthermore, with the burners placed within the furnace, danger of fire is removed.

I prefer to provide a channel 30 which is formed in arcuate shape around the under side of the trough member, and also around the under side of the extensions 12. The purpose of this channel is to receive and partially hold the heat from the burners 29 and to cause the heat to be deflected along the bottom of the trough member in order to distribute the heating effect upon it.

In using the present device the burners 29 will be lighted and the trough member will be placed in the central position shown in Figure 3, so that the flames from the burners will strike under the extensions 12 and heat up the trough member to a degree which will prevent the metal from chilling while it is temporarily flowing in it. A suitable mould is placed within the path of the movable spout 23 and this spout is then positioned to discharge the molten metal in the cavity of the mould. If the mould has a series of cavities, usually the movable spout will be placed over the cavity at one side and the spout will then be shifted as the metal flows into the mould, until all the cavities have been filled. After the burners 29 have heated the trough member and the metal in the metal pot 2 has been raised to the desired degree for pouring, the valve (not shown) commonly used for controlling the discharge of the metal from the connection 3 at the bottom of the metal pot, is opened to allow the molten metal to flow through the stationary spout 4. This spout will discharge the metal into the chamber 11 of the trough regardless of the angular position of the latter. If the trough is in the central position, the stationary spout will discharge the metal into the center of the trough and adjacent the discharge opening 21 and in this case the metal is less likely to spread out in this chamber and will flow through the outlet 21. The metal discharged from the trough chamber through the connection 22 will flow through the movable spout 23 and discharge into the mould chamber. As above stated, the movable spout, with the trough, may be swung while the metal is flowing in order to discharge the metal into the various compartments of the mould. When the mould has been filled, the valve referred to will be closed, and this will shut off the flow of metal through the stationary spout. A portion of the metal may remain in the trough chamber until the next pouring operation; and the heat from the flames of the burners 29 acting on the trough member will prevent this metal from chilling. The operations above described may be repeated as often as desired.

It will be noted that in this construction there are no joints in which the metal can

chill, and interrupt the operation of the device. It also will be apparent that I have avoided the use of a swivel connection between the metal pot and the first spout, so that a non-leaking joint may be formed between these members. Also, by heating the trough member the metal will not chill therein. With the heating means for the trough member arranged inside the furnace, danger of fire is eliminated. By providing the extensions 12 curved inwardly from the arc of the trough chamber, the latter may be swung within the slot 13 in the furnace wall which is about the length that would be required for the chamber portion of the trough alone. With the present device I am able to provide a wide swing for the movable spout in order to cover a mold of large dimensions.

Having described my invention, what I claim is:

1. A metal furnace having a casing and a metal pot therein a stationary member associated with the metal pot for conducting the molten metal to the casing of the furnace, a movable trough member having a chamber arranged to receive the molten metal from said stationary member, and a pouring spout to receive the molten metal from said chamber.

2. A metal furnace having a casing and a metal pot therein, a member associated with the metal pot for conducting the molten metal to the casing of the furnace, a movable trough member having a chamber arranged to receive the molten metal from said conducting member, and a pouring spout movable with said trough member and arranged to receive the molten metal from said chamber.

3. A metal furnace having a casing and a metal pot therein, a conducting member associated with the metal pot for conducting the molten metal to the casing of the furnace, a movable trough member having a chamber with an open top arranged to receive the molten metal from said conducting member in the various positions of the said trough member, and a pouring spout movable with said trough member and receiving the molten metal from said chamber.

4. A metal furnace having a casing and a metal pot therein, a conducting member associated with the metal pot for conducting the molten metal to the casing of the furnace, a curved and movable trough member having a chamber arranged to receive the molten metal from said conducting member, and a pouring spout to receive the molten metal from said chamber.

5. A metal furnace having a casing and a metal pot therein, a conducting member associated with the metal pot for conducting the molten metal to the casing of the furnace, a movable trough member having a chamber to receive the molten metal from

said conducting member, said trough member being of arcuate shape, means for guiding said trough member to rotate in an arcuate path, and a pouring spout movable with 5 said trough member and receiving the molten metal from said chamber.

6. A metal furnace having a casing having a slot and a metal pot in said casing, a conducting member associated with the 10 metal pot and projecting through said casing for conducting the molten metal to the exterior of the furnace, a trough member movable in the slot of said casing and projecting beyond said casing, said trough 15 member having a chamber arranged to receive the molten metal from said conducting member, and a pouring spout outside of said casing moving with said trough member and arranged to receive the molten 20 metal from said chamber.

7. A metal furnace having a casing having a slot and a metal pot in said casing, a spout stationarily connected with the metal pot and projecting through the wall of said 25 casing, an arcuate trough member projecting exteriorly of said casing and movable in the slot in the casing, said trough member having an open chamber arranged to receive the molten metal from said station- 30 ary spout, and a pouring spout movable with said trough member and receiving the molten metal from said chamber.

8. A metal furnace having a casing and a metal pot therein, said casing having a 35 slot, a spout stationarily connected with the metal pot and projecting through the wall of the casing and discharging downwardly, an arcuate trough member having an open chamber to receive the metal from said 40 spout, said trough member projecting from said casing, means for guiding said trough to move in an arcuate path through said slot in said casing, and a pouring spout movable with said trough member and receiving 45 the molten metal from said chamber.

9. A metal furnace having a casing and a metal pot therein, a spout stationarily connected with the metal pot and projecting through the wall of said casing, an arcuate 50 trough member projecting exteriorly of said casing and receiving the metal from said spout, a pouring spout movable with said trough member, said trough member having a chamber for receiving the molten metal 55 from said first spout and provided with a bottom wall inclined toward the outlet of said movable spout.

10. A metal furnace having a casing and

a metal pot therein, a spout connected with the metal pot and projecting through the 60 wall of said casing, an arcuate trough member having an open chamber to receive the metal from said spout, and a pouring spout movable with said trough member and connected with the central portion of said 65 chamber.

11. A metal furnace having a casing and a metal pot therein, means for conducting the metal from said metal pot to the wall of said casing, a movable trough member 70 having a chamber to receive the metal from said conducting means, a movable pouring spout associated with said trough member, and means for heating said trough member.

12. A metal furnace having a casing and 75 a metal pot therein, means for conducting metal from said pot to the wall of said casing, said casing having an opening, a trough member movable in said opening and projecting into the casing, said trough member 80 having a chamber to receive the metal from said conducting means, a pouring spout associated with said trough member and means inside said casing for heating said trough member.

13. A metal furnace having a casing provided with an opening, a metal pot in said casing, a member for conducting metal from said pot through the wall of said casing, a movable, arcuate, trough member projecting from said casing and having a chamber to receive the metal from said conducting member, a pouring spout associated with said trough member, and means in said casing for heating the opposite ends of said 95 trough member.

14. A metal furnace having a casing provided with an opening, a metal pot in said casing, a stationary member associated with the metal pot for conducting molten metal 100 to the exterior of said casing, an arcuate trough member having a chamber to receive the molten metal from said conducting member outside said casing, means for guiding said trough member to move horizontally 105 in an arcuate path through said opening in the casing, said trough member having end extensions extending inwardly from the arc of said trough member, a pouring spout associated with said trough member, and burners arranged within said casing and adjacent the path of said trough member for heating the latter.
